UNITED STATES PATENT OFFICE.

ALBERT GRUNING, OF NEW YORK, N. Y.

DESIGN FOR BOTTLE.

Specification forming part of Design No. **7,606**, dated August 4, 1874; application filed July 3, 1874.
[Term of Patent 3½ years.]

To all whom it may concern:

Be it known that I, ALBERT GRUNING, of New York, in the State of New York, have invented a Design for Bottles, of which the following is a specification:

The nature of my invention is fully represented in the accompanying photographic illustration, to which reference is made.

A represents the body of the bottle, and B the neck of the same. The central part *a* of the body consists of a plain cylindrical ring. The parts *c* and *d* above this central ring *a* are fluted or ribbed, narrowing or tapering toward the top and bottom. The bottom or sole part *n* of the bottle is bulged out to form a base or foot for the bottle to stand on.

The neck *B* of the bottle is made very long and slender.

The distinctive character of my design is found in the cylindrical plain ring *a*, in combination with the ribbed or fluted parts *c* and *d*, above and below the same, and the bulged out foot or base *n*.

What I claim as my invention is—

A design for a bottle, consisting of the central ring *a*, ribbed or fluted parts *c* and *d*, and outwardly-bulged foot *n*, as represented, and substantially in the manner above described.

ALBERT GRUNING.
